CHAIR

William A. Burke, South Bend, Ind., assignor to
 Oriental Wrought Iron Works, Inc., South
 Bend, Ind., a corporation of Indiana

Application October 12, 1940, Serial No. 360,995

2 Claims. (Cl. 155—164)

My invention relates to improvements in chairs.

The invention is designed with the principal object in view of providing a simply constructed chair equipped with a yielding back contributing to comfort of the user and which is adapted for all-around use and is strong and economical to manufacture.

To the accomplishment of the above, and subordinate objects presently appearing, a preferred embodiment of my invention has been illustrated in the accompanying drawing, set forth in detail in the succeeding description, and defined in the claims appended hereto.

In said drawing:

Figure 1 is a view in perspective of the preferred embodiment of my invention,

Figure 2 is a view in side elevation, and

Figure 3 is a view in top plan.

Referring to the drawing by numerals, in the preferred embodiment thereof, my improved chair comprises a pair of side members 1 of tubular form and resilient metal, each embodying a supporting loop including front and rear downwardly converging side stretches 2, 3, forming a front leg, a downwardly bowed stretch 4 connecting said front and rear stretches 2, 3, and forming a foot for said leg, a laterally and inwardly extending stretch 5 forming a continuation of the front stretch 2 and a seat support, and an upright substantially straight stretch 6 comprising an extension of the rear stretch 3 rising above the lateral stretch and forming a back supporting post.

The side members 1 are connected together by a yoke member 7, also of tubular form and resilient metal and which is of substantially inverted U-shape. The yoke member 7 straddles the side members 1 and embodies a straight front stretch 8 extending across the front stretches 2 at the level of the lateral stretches 5, and a pair of side stretches 9 extending along the outer sides of the lateral stretches 5 parallel therewith to form seat supports and curving from said stretches 5 downwardly and rearwardly across the rear stretches 3 to form rearwardly bowed rear legs for the chair.

The side stretches 9 are welded to the lateral stretches 5, the welding not being shown, and detached from the rear stretches 3, the latter together with the post forming stretches 6 being free to flex forwardly and rearwardly to provide an easy yielding back rest.

Suitable seat and back members 10, 11, of cushion form, as shown in dotted lines in Figures 1, 2,

are fixed in any desired manner to the described seat forming supports 5, 8 and 9, on the one hand, and to the post forming stretches 6 on the other hand.

As will now be seen, my invention provides a strong chair construction which will afford the maximum comfort at a minimum cost of manufacture and which is practically indestructible, and adapted for use either outdoors or indoors.

10 The foregoing will, it is believed, suffice to impart a clear understanding of my invention without further explanation.

Manifestly the invention, as described, is susceptible of modification without departing from the inventive concept and right is herein reserved to such modifications as fall within the scope of the subjoined claims.

What I claim is:

1. A chair comprising a pair of side members 20 of tubular form and resilient metal each embodying a supporting loop including front and rear side stretches converging downwardly and being connected to form a front leg, the front stretch having a lateral inwardly projecting extension forming a seat support, and the rear stretch having an upstanding extension forming a back supporting post, and a yoke member of tubular form and resilient metal, straddling said side members and having a pair of side stretches fixed to the 25 side stretches of said side members and extending downwardly and rearwardly across said rear stretches to form rear legs for the chair.

2. A chair comprising a pair of side members 35 of tubular form and resilient metal each embodying a supporting loop including front and rear side stretches converging downwardly and being connected to form a front leg, the front stretch having a lateral inwardly projecting extension forming a seat support, and the rear stretch having an upstanding extension forming a back supporting post, and a yoke member of tubular form and resilient metal, straddling said side members and having a pair of side stretches fixed to the 40 extensions of said side members and extending downwardly and rearwardly across said rear stretches to form rear legs for the chair, the extensions of said side members being detached from the rear stretches of said side members and the side stretches of the yoke being detached from the rear stretches of said side members whereby

45 said rear stretches and upstanding extensions thereof are free to flex back and forth.

WILLIAM A. BURKE.
